FUSE CONSTRUCTION

Piao, Kiang, Washington, D. C.

Application July 31, 1942; Serial No. 453,069

1 Claim. (Cl. 102—75)

1

The present invention relates to a fuse construction for explosive projectiles.

It is a principal object of my invention to provide a fuse construction of the set-back type especially adapted to be used with smooth bore explosive projectiles of the non-rotating type, such as may be used in the smooth bore barrels of trench mortars or the like.

It is a very important object of my invention to provide a fuse construction which is not only bore safe, but is absolutely safe and maintained in an unarmed condition until after the fuse with its projectile has reached its maximum ordinate and is falling towards the ground.

It is also an important object of my invention to provide a fuse construction having two functions of either super-quick or delayed action especially adapted to be used with smooth bore projectiles and having means for selectively adjusting the fuse to give either a delayed or a super-quick action, together with means to lock the selecting means in the selected position immediately upon the projection of the fuse with its projectile from the barrel of the projecting device.

It is a further object of the present invention to provide a fuse construction of the character described which is absolutely safe for handling and storage purposes and which is positively locked against arming until the fuse with its projectile has been projected from the barrel of the projecting device and has passed its maximum ordinate.

It is also an object of the present invention to provide a fuse construction especially adapted to be used with smooth bore projectiles and having selected functions of delayed or super-quick action with a simple means for selecting either of the desired fuse actions merely by a manual rotation of the fuse body before placing the fuse with its explosive projectile in the barrel of the projecting device.

It is a still further object of my invention to provide a fuse construction in which all operating features are fully enclosed and are rendered completely air and water-tight.

Further objects and advantages of my invention will be apparent by reference to the following specification and drawings in which:

Figure 1 is a longitudinal section of the fuse of my invention with the parts locked in inoperative position to prevent an arming of the fuse;

Figure 2 is a longitudinal section similar to Figure 1 but with the parts shown in the position assumed immediately upon projection of the fuse and its projectile from the barrel of the projecting device;

Figure 3 is a longitudinal section partly in elevation of the fuse, showing the parts in the armed

2

position assumed when the shell is falling toward the ground;

Figure 4 is a longitudinal section partly in elevation, taken at right angles to Figure 1, and showing the selecting means adjusted to select a delayed action for the fuse;

Figure 5 is a horizontal section taken on the line 5—5 of Figure 4;

Figure 6 is a fragmentary longitudinal section, 10 showing the details of the selecting slide with the slide locked in the position to select a super-quick action of the fuse;

Figure 7 is a horizontal section taken on the line 7—7 of Figure 1, further illustrating the selecting slide;

Figure 8 is a horizontal section taken on the line 8—8 of Figure 6, and;

Figure 9 is a fragmentary enlarged section taken on the line 9—9 of Figure 1, showing the details of the safety bolt for locking the fuse against arming before the projection of the fuse and its projectile.

Referring to Figure 1 of the drawings, a fuse body 9 is provided with threads 10 for attachment to an explosive projectile. At the nose end of the body 9, a fuse nose ring 11 of rolled metal is secured in place to retain a fuse nose cup 12 of thin metal. The fuse body 9 is provided with a longitudinal bore of varying dimensions. At the nose end, the fuse body bore is enlarged as at 13 to provide a shoulder 14, upon which is seated the firing pin cup 15 which is retained in place by the fuse nose cup 12 and ring 11. Seated within the firing pin cup 15 and secured in any suitable fashion is a firing pin 16. It should be noted that the fuse nose ring 11 is secured to the body 9 in such manner as to render the operating mechanisms within the fuse body completely air and watertight.

Slidably positioned within the bore 17 is the body 18 known as a primer adapter or carrier. The primer adapter body 18 is provided with a longitudinal bore and seated within the bore at a central point along its length is the primer 19. The primer 19 is retained in position by the threaded collar 20. The longitudinal bore 21 of the primer adapter body 18 is constricted at its rearward end to provide a seat for a safety ball 22 which, when in position shown in Figures 1 and 2, prevents the firing pin 16 from striking the primer 19 to ignite the fuse and thus maintains the fuse in an unarmed condition.

The primer adapter body 18, which is slidably positioned within the bore 17, is normally locked 55 against sliding movement in any direction. The locking means is releasable by inertia upon the projection of the fuse and its shell from the projecting barrel. To prevent the primer adapter body from sliding forwardly towards the nose of the fuse, a locking means is provided comprising

ing a safety ball 23 resting in a groove 24 of the primer adapter body 18 and also abutting a shoulder 25 formed on the wall of the bore 17 in the body 9 of the fuse. With the safety ball 23 in the position shown in Figure 1 of the drawings, it will be seen that the primer adapter body 18 is prevented from sliding forwardly toward the nose of the fuse. The locking means to prevent a sliding movement of the primer adapter body 18 in a rearward direction towards the main body of explosive charge comprises a safety bolt or plunger 26 of circular cross section. The safety bolt 26 which is maintained in the position shown in Figure 1 when the fuse is locked and unarmed is slidably positioned within a bore 27 of the fuse body 9 and a bore 45 in the delay casing 35. Spring fingers 28, as shown in detail in Figure 9 of the drawings, engage against a shoulder formed by the flattened surfaces 29 at the end of the safety bolt 26, thus holding the safety bolt in the position shown in Figures 1 and 9 of the drawings and preventing any sliding movement of the primer adapter body 18 toward the rear of the fuse body. The thickness and the tensile strength of the spring fingers 28 may be varied or adjusted to the requirements of the individual fuse with its projectile.

Referring to Figure 2 of the drawings, immediately upon the projection of the fuse and its projectile from the barrel of the projecting device such as a trench mortar or the like, the inertia of the primer adapter body 18 will be sufficient to overcome the pressure of the spring fingers 28 against the shoulders formed by flattened surfaces 29 of the safety bolt 26 and will force the safety bolt 26 to move rearwardly within the bore 27 and bore 45 to assume the position shown. Thus, the primer adapter body 18 will be slid rearwardly by inertia within the bore 17 to assume the position shown in Figure 2 of the drawings, and in this position will enable the safety ball 23 to fall out of the groove 24 and be freed within the enlarged part 30 of the bore 17 in the fuse body 9. Thereafter the fuse will be in a position to be armed and the primer adapter body 18 will be free to slide forwardly towards the nose of the fuse when such a directing force is applied.

As the fuse and its projectile pass the peak of its trajectory or its maximum ordinate after being fired from a trench mortar or the like and is commencing to fall towards the earth, the safety ball 22 will fall out of the bore 21, and the primer adapter body 18 can slide forwardly within the bore 17 towards the nose of the fuse, as shown in Figure 3 of the drawings. Since the safety ball 22 is no longer resting within the bore 21, the point 31 of the firing pin 16 can contact directly upon the casing 32 of the primer 19 when the primer adapter body 18 has moved forwardly. Thus the fuse will be armed and upon impact, the firing pin 16 will explode the primer 19 to ignite the fuse.

I have described thus far a set-back fuse which is especially intended to be used with explosive projectiles of the smooth bore or non-revolving type, such as are used in the barrels of trench mortars or the like. This fuse construction which I have described is exceedingly safe, since the fuse is normally locked to maintain the fuse in an unarmed condition in which it is absolutely impossible for the firing pin to strike the primer. However, the locking means for the fuse construction as described is releasable by the inertia obtained upon the projecting of the fuse and its

projectile from the barrel of the projecting device. With the fuse construction embodying the locking device of my invention, it is absolutely safe to store and handle explosive projectiles to which the fuse has already been attached in a condition which, upon placing in a projecting device and upon projection to a point past its maximum ordinate will result in an immediate arming of the fuse.

I have also embodied in the fuse construction of my invention, a means for giving either a delayed or super-quick action of the fuse for ignition of the explosive charge. The means for selecting either the delayed or super-quick action of the fuse upon impact is exceedingly simple and fool-proof and does not necessitate the use of tedious fine adjustments located on the outside of the fuse body.

Referring to Figures 4 through 8 of the drawings, which show the details of the selecting device for selectively adjusting the fuse to give either a delayed or super-quick action, a bore 33 within the body 9 is provided to conduct the flame from the exploded primer 19. Positioned within an enlarged bore 34 adjacent to the bore 33 is a body 35 constituting a delay case and housing, the selecting slide and delay powder charge, as will be described hereinafter. A thin metal plate or safety disc 36 is interposed between the bore 33 and the delay case 35 and functions as a gasket responsive to the pressure of the flame from the primer 19 to seal the delay case 35 with respect to the body 9 of the fuse and prevent a blow-by of flame such as would result in an immediate explosion of the main explosive charge even if the fuse is set to a delayed action. The disc 36 also is punctured, as shown in Figures 5 and 9 of the drawings, to form the spring fingers 28 for locking the safety bolt 26, as described previously in connection with Figures 1 and 9 of the drawings. Slidably positioned in a transverse passage in the delay case 35 is the selecting slide 37. The selecting slide 37, as shown in Figures 6 through 8 of the drawings, is provided with a bore 38 and an imperforate bore 39. When the slide 37 is in the position shown in Figures 6 and 8 of the drawings, the bore 38 is in alignment with the bore 40 of the delay casing 35 to provide a direct through-passage for the flame from the primer 19 to reach the main body of explosive charge. With the parts in this position providing a direct through-passage for the flame, a super-quick action of the fuse is obtained.

For a delayed action the slide is moved to the position shown in Figures 2, 4, and 7 of the drawings, and when the slide is in this position, the imperforate bore 39 is in alignment with the bore 40, thus blocking off a direct passage for the flame in the chamber 33 to the main body of explosive charge. The pressure of the flame and burning gases within the imperforate bore 39 will seat the slide tightly within the delay case 35, thus preventing the blow-by of any flame such as would effect a super-quick action of the fuse. With the passage 40 blocked by the imperforate bore 39, the flame from the primer and in the bore 33 must pass through the charge of delay powder 41 and the relay powder 42 to reach the main body of explosive charge, thus giving a delayed action to the fuse. As will be seen in Figure 4 of the drawings, the delay powder 41 is in the form of a threaded core and is threaded within the delay case 35. The threads serve to prevent the displacement of the delay powder by any

rough handling of the fuse. Also, as shown in Figure 4 of the drawings, the relay powder 42 for conducting the burning flame from the delay powder 41 to the main body of explosive charge is held in position by the threaded collar 43. It will be seen that when this threaded collar 43 is removed from the body 9, the relay powder ring 42 may be removed and the delay case 35 containing the slide 37 and delay powder 41 may likewise be removed for inspection or repairs.

As described above, the slide 37 may be moved to the position shown in Figure 6 of the drawings to give a super-quick action or may be moved to the position shown in Figures 2 and 4 to give a delayed action of the fuse. To move the slide 37, it is only necessary to rotate the fuse and its shell before placing the shell in the barrel of the projecting device. An indication 44 on the surface of the fuse body 9 is provided, and it is preferably a depression which may be felt by the operator so that the fuse may be manipulated in total darkness, if necessary. When the fuse is rotated so that the depression 44 is facing upward, the slide will move in response to gravity to assume the position shown in Figure 6 of the drawings and select a super-quick action of the fuse. When the fuse and projectile are rotated to a position with the indication 44 facing downward, the slide 37 will be moved in response to gravity to the position shown in Figures 1 and 2 of the drawings and select a delayed action for the fuse.

The selecting device, as described above, is so designed as to be locked in the selected position immediately upon the projection of the fuse and its projectile from the barrel of the projecting device. Upon projection of the fuse and its projectile, the set-back inertia of the primer adapter body 18 is sufficient to force the safety bolt 26 to move past the spring fingers 28 within the bore 45 of the delay case 35, as previously described, to assume either of the positions shown in Figures 2 and 6 of the drawings. When the selecting slide 37 is in the position shown in Figure 6 of the drawings, the safety bolt 26, when moved in response to the inertia of the primer adapter body 18, will be moved through the bore 45 to a position behind the slide 37, thus preventing any further movement of the slide 37 and locking the slide in the selected position to give super-quick action of the fuse. If the slide is in the selected position, as shown in Figure 2 of the drawings, for giving a delayed action of the fuse, the safety bolt 26 will pass, when moved in response to the inertia of member 18, through the bore 38 in the slide to lock the slide in this selected position of delayed action. It should be noted that the safety bolt 26 is of circular cross section with the exception of the flattened end surfaces 29, and that when the safety bolt 26 is moved to the position shown in Figures 2 and 6 of the drawings, the spring fingers 28 will frictionally grip the enlarged circular cross section of the safety bolt 26, so that the safety bolt 26 cannot thereafter be moved, and thus assuring that the selecting slide 37 will remain locked in the desired position.

I have shown and described a fuse for explosive projectiles especially adapted to be used with smooth bore or non-rotating projectiles which is absolutely safe for storage and handling purposes and which is normally locked to maintain the fuse in an inoperable or unarmed condition

until the fuse and its projectile are projected from the barrel of the projecting device. The locking means, as shown and described, is automatically releasable by the forces of inertia obtained when projecting the fuse with its projectile from the barrel of the projecting device to permit the arming of the fuse by the turning over of the fuse with its projectile after passing its maximum ordinate. The fuse construction which I have invented is also provided with a means for giving either a delayed or super-quick action upon impact and with a simple and easily operable means for selecting either the delayed or super-quick action. It will be noted that the means for selecting either the delayed or super-quick action of the fuse is operable in response to a manual rotation of the fuse body before the fuse and its projectile are placed in the barrel of the projecting device, and since the selecting operation is so simple, it may be done without resort to fine adjustments and in total darkness, with absolute certainty as to the selected action of the fuse.

It should be understood that while the fuse construction which I have shown and described is particularly adapted to be used with smooth bore or non-rotating explosive projectiles, the fuse construction as shown and described is also capable of being applied and used to advantage with rotating projectiles, if desired, since the fuse and the fuse controlling means are responsive to the forces of inertia as obtained in any explosive projectile immediately upon the projection of the projectile from the barrel of the projecting device.

It is to be understood that the construction shown and described is merely an illustration of the preferred embodiments and that such changes may be made as fall within the purview of one skilled in the art without departing from the spirit of the invention and the scope of the appended claim.

I claim:

A shell fuse comprising a body having an axial bore, a carrier slidable in said bore, a primer carried by said carrier, a rearwardly projecting firing pin in the forward end of said bore against which the carrier is adapted to carry the primer, means normally locking said carrier against forward movement in said bore intermediate the ends of the latter and with the primer spaced from the firing pin, said locking means being released to permit such forward movement upon relative rearward movement of said carrier in said bore due to set-back inertia, said body defining a pair of axially extending firing paths behind the primer and a transverse passage intersecting one of said paths, control means freely slidable in said channel by gravity between blocking and freeing positions with respect to said one of said paths, a plunger mounted in said body for relative axial sliding movement, and means holding said plunger in a normal position wherein said plunger engages said carrier to hold said carrier in its normal position, said holding means being released due to set-back inertia of said plunger and carrier so that said plunger and carrier move relatively rearwardly with respect to said body to positions wherein the locking means for the carrier is released and the plunger locks said control member in selected position.

PIAO KIANG.
